UNITED STATES PATENT OFFICE

AUGUSTUS HASBROUCK, OF NEW HAVEN, CONNECTICUT

REMOVABLE VALVE CAGE FOR INTERNAL-COMBUSTION ENGINES

Application filed May 4, 1929. Serial No. 360,418.

This invention relates to improvement in removable valve-cages for either the intake or exhaust ports of an internal combustion engine particularly designed for air-cooled engines. The object of this invention is to provide a valve-cage which may be readily removable if desired but which will closely fit the cylinder head to which it is attached, and the invention consists in the construction as 10 hereinafter described and particularly recited in the claims.

In the accompanying drawings:

Fig. 1 is a sectional view illustrating a removable valve-cage for internal combustion engines constructed in accordance with my invention; and

Fig. 2 is a perspective view of the valve-seat detached.

In carrying out my invention I employ a 20 valve-cage body 5 supporting a valve 6, the stem 7 of which extends through a sleeve 8 mounted in the cage. On the outer end of the stem is a flanged collar 9 and between the flange and cage is a valve-spring 10. The 25 valve extends through a neck 11 formed integral with the cage and surrounding the neck and closely fitting the same is a valve-seat 12 onto which the valve is normally forced by the spring 10. This seat is mounted 30 in an opening 13 in the cylinder head 14 of an internal combustion engine in which it has an easy fit to permit its ready insertion or removal.

The seat has an annular flange 15 and the cage a similar flange 16 which bear upon the surface of the cylinder head to which they are attached by screws 18. Preferably, a gasket 19 will be inserted between the flange 15 and the cylinder head.

The valve-cage body and cylinder head are preferably formed from aluminum alloy having a high coefficient of linear expansion, while the valve-seat is formed from bronze 45 alloy having a lower coefficient of linear expansion, so that as the neck of the cage expands, it will tightly engage the valve-seat and, in turn, force the valve-seat against the opening in the cylinder head and cause it to 50 make a close contact therewith and provide a

ready path for the transference of heat from the seat to the cylinder head.

Another factor responsible for the close contact between the neck of the valve-cage, the annular valve-seat, and the cylinder-head, 55 resides in the fact that in operation the three parts in the order named are maintained at different degrees of temperature, for instance, the valve-cage being maintained at the highest temperature; the valve-seat at the intermediate temperature; and the cylinder-head at the lowest temperature, relative to the others, 60 so that the highly-heated neck of the valve-cage expands to a relatively-great degree and tightly engages the inner periphery of the valve-seat which, in turn, is stretched into close engagement with the opening in the cylinder-head by the expansion of the said neck. It will be understood, as above stated, 65 that the cylinder-head itself does not expand to the same degree as the neck of the valve-cage for the reason that it is maintained at a much lower temperature by the action of cooling-fins or cooling water, dependent on whether or not the engine is of 70 the air-cooled or water-cooled type.

I thus provide a construction by which the transference of heat from one member to another is controlled and which permits the ready removal of the cage from the cylinder 75 when desired, when the parts are at atmospheric temperatures.

I claim:

1. The combination with a cylinder head having an opening, of a valve-cage formed 80 with a neck, a valve-seat surrounding and closely fitting said neck and adapted to enter the said opening in the cylinder head to which the cage and seat are secured, and a valve mounted in the said cage to co-act with said seat.

2. The combination with a cylinder head having an opening, of a valve-cage formed 85 with a neck, a flange above said neck, a valve-seat surrounding and closely fitting said neck 90 and adapted to enter the said cylinder head and formed with a flange, said flanges secured to the cylinder head around the opening therein, and a valve mounted in the said cage to co-act with said seat.

3. The combination with a cylinder head having an opening, of a valve-cage formed with a neck, a valve-seat surrounding and closely fitting said neck and adapted to enter the said cylinder head to which the cage and seat are secured, and a valve mounted in the said cage to co-act with said seat, the cylinder head and valve-cage having a relatively high coefficient of linear expansion and the valve-seat having a relatively lower coefficient of linear expansion.

In testimony whereof, I have signed this specification.

AUGUSTUS HASBROUCK.
